UNITED STATES PATENT OFFICE.

HUGH J. SCANLON, OF MCKEESPORT, PENNSYLVANIA, ASSIGNOR TO AMERICAN SHEET & TIN PLATE COMPANY, OF PITTSBURG, PENNSYLVANIA, A CORPORATION OF NEW JERSEY.

CONTINUOUS PICKLING AND TINNING APPARATUS.

No. 893,383.

Specification of Letters Patent.

Patented July 14, 1908.

Application filed April 19, 1905. Serial No. 256,409.

To all whom it may concern:

Be it known that I, HUGH J. SCANLON, of McKeesport, Allegheny county, Pennsylvania, have invented a new and useful Continuous Pickling and Tinning Apparatus, of which the following is a full, clear, and exact description, reference being had to the accompanying drawings, forming part of this specification, in which—

10 Figure 1 is a top plan view showing one form of my improved apparatus; and Fig. 2 is a vertical longitudinal section of the same.

15 My invention relates to apparatus for continuously pickling and tinning sheets of metal without the use of hand operators.

Heretofore in the practical operation of coating metal, considerable hand labor has been necessary in connection with the pickling and coating operations.

20 The object of my invention is to do away with hand labor and provide means for continuously pickling and coating sheets of metal.

In the drawings, in which I show a preferred form of my apparatus, 2 represents the pickling vat, which may be of any desirable form, and 3 is a feeding device consisting of a shaft having several series of projecting radial arms 4 secured to rings or collars 30 5 on the shaft. The arms force the plates down and through the bath between the two sets of guides 6 and 6'. Each set of guides preferably consists of rods spaced between push-arms of the shaft and extending across 35 the pickling vat at separated points. The guides are so arranged relatively to the feeder-arms that the sheets will be pushed successively down into the pickling bath and thence upwardly through its other portion.

40 Above the feed-out ends of the guides are placed feed-out and wiper-rolls, which may be of any desirable construction. I prefer, however, to arrange them in three sets as follows:—The lower set 7, 7 are preferably 45 rubber rolls, which act to squeeze the liquor from the sheet. These rolls are preferably driven at the same speed as that of the rising sheet and are provided with ordinary adjusting screws to adjust the squeezing action.

50 Above the roll 7, a second set of rolls 8 in line therewith are driven at a higher peripheral speed than the rolls 7. This may be done either by making the rolls 8 of larger diam-

eter or by arranging their driving connections to drive them faster. The rolls 8 are preferably formed of longitudinal rubber strips secured close together upon a cylindrical base of wood, or any suitable material. Springs 8' are preferably provided between the end bearings of these two rolls, the bearings also being provided with adjusting screws. Owing to the speed of these rolls being higher than that of the metal passing through, they will produce a scraping and cleaning action which will remove any dirt or scale left on the plate, and also assist in removing any moisture which might remain. Above the rolls 8 I employ a set of rolls 9, which are the same character as the rolls 7. These rolls 9 hold back the plate in the rolls 8 after it has left the rolls 7 and compel the rolls 8 to exercise their scraping action on all parts of the plate.

The rolls 9 feed the plate upwardly within the backwardly curved guide 10. This guide consists of a series of bars or strips which are reversely bent leaving open mouths at their bottom ends. They are inclined backwardly or over the bath so that after the sheet has been fed up within them it will slide back and drop down the chute 11. This chute is preferably in rack or skeleton form, as shown in Fig. 1, and water is preferably sprayed upon the sheets by a spray-pipe 11^a located over the chute. This water serves to wash away any remaining traces of acid or pickle liquor, and thus better prepare the sheets for the coating operation. It also prevents oxidation of the surface of the sheets. The spray-pipe may or may not be used, as desired, and I do not intend to limit myself thereto in my broader claims. As the sheets slide down the chute 11 they enter the inclined set of feed-rollers 12 which are within the flux box or chamber 13 of the tinning pot 14, one or both of these rollers preferably turning within the flux. The housings 15 for these feed-rollers 12 hang within the pot and are supported by straps 16 which are bolted to the supporting plate 17. From the rollers 12 the sheets pass down through the flux box 13 into the feed-rollers 18. The lower part of the flux box is preferably perforated to allow the metal to circulate freely below the flux at its proper level. The rolls 18 are preferably spring-pressed similarly to the rolls 12, and feed the sheets from the flux side of the tin-

ning pot into the metal side in which the tinning rolls may be arranged in the ordinary manner. I have shown the tinning rolls as driven from a worm-gear driving-head in the 5 usual manner.

The different rolls and the pickle-bath feeder may be driven by any desirable connections. In the form shown, a sprocket-chain 19 leads from a sprocket-wheel on the 10 drive-shaft 20 of the tinning rolls to a sprocket wheel on the extended shaft 21 of one of the upper rolls 9. The shafts of the two rolls 9 are geared together at this end by the toothed wheels 22 and 23, and a sprocket-chain 24 15 leads from a sprocket-wheel on one of these shafts down to a similar sprocket-wheel on the shaft of one of the rollers 12 of the flux box. From the other end of one of the rollers 12 a sprocket-chain connection 25 leads 20 down to one of the rolls 18 to drive these rolls which are geared together at opposite ends, as shown in Fig. 1. The rolls 12 are also similarly geared together as shown in this figure. At the end of one of the rollers 9 25 opposite to the sprocket-wheel end a large toothed wheel 26 intermeshes with a similar toothed wheel 27 on the shaft of one of the rolls 8. These two rollers are geared together at their ends opposite to the wheel 27 30 so that they are rotated simultaneously at a higher speed than the rolls 9. The smaller toothed wheel 27 upon the shaft of one of the rolls 8 drive a larger toothed wheel on the shaft of one of the rollers 7, which shaft is 35 geared to the other roller at the opposite end, thus driving both of these rollers 7. On the end of the left-hand roller 7 is a toothed wheel 28, which intermeshes with an idler wheel 29 rotating loosely on the shaft of the 40 other roll 7, and intermeshing with a large driving gear wheel 30 secured to the shaft 31 of the feeding device for the pickling bath.

32 are conveyer rolls, 33 are the bottom rolls of the tin machine, and 34 are the upper 45 sets of tinning rolls mounted in the usual housings 35.

The preferred level of the tin bath is shown by the dotted line $a-a$ of Fig. 2.

In the operation of the device, the sheets 50 are fed singly and successively either by hand or otherwise between the spokes or arms of the feeder wheel 3. The feeder forces these sheets successively through the pickling bath; and as they rise the liquor is 55 squeezed off by one set of rolls, and the next set running at a higher speed scrapes and cleans the surfaces of the sheet while further assisting in removing the liquor. The sheets are then forced up by the upper feed 60 rolls into the reverse inclined guide, and thence slide back down the chute into the flux-box rollers, by which they are fed into the lower feed-rollers on the flux side, and thence into the ordinary tinning rolls which 65 feed the sheets up out of the pot.

The advantages of my invention result from the reduction of hand labor, in the pickling and tinning operations; the operation of the machine is rapid, the pickling is uniform on the successive sheets, and the labor 70 cost is reduced.

Many variations may be made in the form and arrangement of the pickling bath, the tinning pot, the feeding means, &c., without departing from my invention.

I claim:

1. The combination with a pickling bath and a tinning machine, of means for feeding sheets downwardly and thence upwardly through the pickling bath, and means for 80 feeding the sheets rear end foremost into the tinning bath; substantially as described.

2. A tinning machine having a flux compartment, feed rolls within the upper part of the flux compartment above the level of the 85 tin, and arranged to rotate within the flux bath, a pickling bath adjacent to the tinning machine, and intermediate feed mechanism arranged to feed the sheets rear end foremost from the pickling bath into the flux 90 rolls; substantially as described.

3. In pickling and tinning apparatus, the combination with a tinning machine, of a pickling bath, means for feeding the sheets therethrough, rolls arranged to carry the 95 sheets upwardly as they emerge from the bath, and an inclined chute for delivering the sheets to the tinning machine, said chute being arranged to receive the sheets from said rolls and feed them rear end foremost 100 to the tinning machine; substantially as described.

4. In pickling and tinning apparatus, the combination with a pickling bath and a tinning machine, of a combined feed-out and 105 wiping device intermediate of the pickling bath and tinning machine, said device comprising three sets of rolls, the middle set having a higher peripheral speed than the adjacent sets; substantially as described.

5. In pickling and tinning apparatus, the combination with a pickling bath and a tinning machine, of a combined feed-out and wiping device intermediate of the pickling 115 bath and tinning machine, said device comprising three sets of rolls, the middle set having a higher peripheral speed than the adjacent sets, and also having peripheral wiping devices; substantially as described.

6. In continuous pickling and tinning apparatus, the combination with a pickling bath, of a feed-out device therefor, comprising a plurality of sets of rolls, an intermediate set of which has a higher peripheral speed than the other sets, means for forcing 120 said rolls with a yielding pressure against the sheet as it passes through a tinning machine and means for delivering the sheets from said feeding-out device to the tinning machine; substantially as described.

7. In pickling and tinning apparatus, the combination with a pickling bath and a tinning machine, of means for feeding the sheets through the pickling bath, feed-out means for said bath, consisting of upper and lower sets of rolls of yielding material, wiper rolls intermediate of the upper and lower rolls and having a greater peripheral speed, a tinning machine, and means for automatically delivering the sheets from said rolls into the tinning machine; substantially as described.
- In testimony whereof, I have hereunto set my hand.

HUGH J. SCANLON.
